(57) **CLAIM**

The ornamental design for a dental material dispenser cartridge and tip, as shown and described.

DESCRIPTION

FIG. 1 is an isometric view of a dental material dispenser cartridge and tip showing our new design;

FIG. 2 is a first side view thereof;

FIG. 3 is a second side view thereof;

FIG. 4 is a rear view thereof;

FIG. 5 is a front view thereof;

FIG. 6 is a top view thereof; and,

FIG. 7 is a bottom view thereof.

The broken lines shown in the figures are included for the purpose of illustrating portions of the dental material dispenser cartridge and tip and form no part of the claimed design.

1 Claim, 5 Drawing Sheets
